CONVERTIBLE TOOL

Aaron Shaffer, Saginaw, Mich.

Application July 10, 1935, Serial No. 30,668

1 Claim. (Cl. 145—52)

The invention relates to a tool and more especially to a combination or convertible tool.

The primary object of the invention is the provision of a tool of this character, wherein the same is adaptable either as a screw driver or as a plug wrench and when serving as a screw driver the screw operated upon can be held so that a positive and a straight screwing action by the screw driver member is assured and in this manner eliminating the necessity of the hand guiding of the screw when being initially set in the work or during the screwing home thereof.

Another object of the invention is the provision of a tool of this character, wherein the plug wrench will be held positively engaged with work and associated with the tool is an electric light so that in the use thereof in hidden or dark places the tool can be successfully operated when used as a screw driver or a wrench.

20 A further object of the invention is the provision of a tool of this character, which is simple in construction, thoroughly reliable and efficient in its operation, readily and easily converted, strong, durable, and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

In the accompanying drawing:

35 Figure 1 is a perspective view of the tool in use as a screw driver.

Figure 2 is a perspective view of the wrench member for the tool, it being separated from adjuncts thereof.

40 Figure 3 is a fragmentary sectional view showing a nut worked upon by the wrench member of said tool.

Similar reference characters indicate corresponding parts throughout the several views in the drawing.

45 Referring to the drawing in detail, the tool comprises a screw driver member A including a straight shank 10 having formed at one end a screw engaging tip or blade 11 while at the opposite end is a handle 12 as is customary. This shank 10 of the member A is slidably fitted in a guide eye or sleeve 12' formed from an ear 13 separably receiving a pivot bolt 14 swingingly connecting it between convergent side arms of a substantially U shaped bracket 15 to the closed flat end 16 of which is pivoted by a pivot bolt 17

a pair of crossed hand operable levers 18, these carrying handles 19 close to the handle 12 of the shank 10 and are formed with parallel jaw ends 20 disposed at right angles to the said levers 18 for clamping therebetween a screw or the like 21, the jaws at the inner sides thereof being formed with outstruck seats 22 for the screw 21 to hold it in a position for alignment with the blade 11 of the shank 10 of the screw driver member. This blade 11 as usual is engaged in a cross cut 23 in the head of the screw so that the latter may be turned for the driving home of the said screw or its removal from a piece of work. The jaws 20 not only serve as a clamp or holding and guide means for the screw 21, but also as a rest or support for the tool.

Surrounding the shank 10 of the screw driver member A and working against an abutment washer 24 upon said shank and seated upon the latter next to the blade 11 is a coiled expansion spring 25, it being also seated against a washer 26 on the shank 10 next to the guide sleeve 12 which under the expansion of the spring 25 rests against the said sleeve 12 and this spring serves to feed the screw driver member A against the screw 21 when the same is being driven home in a piece of work. Thus the screw driver member A when engaged with the screw 21 and the latter is clamped by the jaws 20 will be held in contact and in feeding relation to the screw.

30 The levers 18 next to the jaws 20 are outwardly bulged as at 27 and to these bulged portions are fixed hangers 28 for a coiled retractile spring 29 functioning to draw the jaws 20 toward each other to have the same clamp the screw 21 when arranged between the jaws. The screw 21 is released from the jaws 20 when the levers 18 are operated to spread the said jaws apart.

35 In lieu of the screw driver member A there can be attached to the bracket 15 the ear 30 having the guide sleeve 31 for slidably holding the stem 32 of a plug or socket wrench. This stem 32 is fitted at one end with a flat faced head 33 functioning as a plug wrench and such head is engageable with a socket unit 34 for wrench action upon a nut 35. The stem 32 at the other end carries a handle 36 similar to the handles 12 and 19 excepting that there is pivoted to this handle 36 a swinging handle extension 37 which is capable of being thrown at right angles to the handle 36 to give leverage in the operation of the stem 32 during the use of the plug or socket wrench.

50 Upon one of the levers 18 is detachably and adjustably clamped a holder 38 for an electric lamp 55

39, it having the usual electric cord 40 and separable terminal plug 41 so that the latter can be inserted in an electric plug socket for supplying current from an electric light source to the lamp 5 39 for illumination or the lighting thereof, the holder 38 being adjustable for the projecting of the light on to the screw 21 or nut 35 in the use of the tool as a screw driver or wrench by conversion thereof so that in either event the part 10 worked upon will be clearly visible to the user of the tool either in a hidden area or during darkness.

What is claimed is:

A tool for the purpose set forth, comprising a pair of crossed levers having handle ends and parallel jaw ends which are arranged at right angles to the levers, a bracket extending parallel to the direction of the jaw ends and pivoted to the levers at the point of crossing of said levers, a sleeve pivoted to the bracket, a tool shank revolvably in and longitudinally movable through said sleeve, spring means urging the shank in a direction towards the jaw-ends and spring means connected to the levers for influencing the jaw ends thereof toward each other. 5

AARON SHAFFER.
